(57) **CLAIM**

We claim the ornamental design for a portable speaker for audio player, as shown and described.

DESCRIPTION

FIG. 1 is a perspective view of a portable speaker for audio player showing a first embodiment of our design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a perspective view of an alternative embodiment of FIG. 1;

FIG. 9 is a left side elevational view of FIG. 8; and,

FIG. 10 is a right side elevational view of FIG. 8.

The broken lines showing on the drawing disclosure are for illustrative purposes only and form no part of the claimed design.
